(57) **CLAIM**

The ornamental design for a plug and jack system for a magnetic audio connector, as shown and described.

DESCRIPTION

FIG. 1 is a perspective view from the front and one side of the jack component for our new design of a plug and jack system for a magnetic audio connector, the jack component being shown separately for illustrative clarity;

FIG. 2 is a perspective view from the rear and left side thereof; FIG. 3 is a perspective view from the rear and right side thereof;

FIG. 4 is a front elevational view thereof;

FIG. 5 is a left side elevational view;

FIG. 6 is a rear elevational view;

FIG. 7 is a perspective view from the front and one side of the plug component for our new design of a plug and jack system for a magnetic audio connector, the plug component being shown separately for illustrative clarity;

FIG. 8 is a front elevational view thereof;

FIG. 9 is a left side elevational view thereof, the left and right side elevational views being the same; and,

FIG. 10 is an exploded perspective view of our new design of a plug and jack system for a magnetic audio connector.

The broken line portion of the figure drawings is included to show unclaimed subject matter only and forms no part of the claimed design.

1 Claim, 7 Drawing Sheets
